UNITED STATES PATENT OFFICE

94,571

DESIGN FOR AN ATTACHABLE SHELF

Jean Schimmelfeng, Chicago, Ill.

Application November 22, 1934, Serial No. 54,120

Term of patent 3½ years

To all whom it may concern:

Be it known that I, Jean Schimmelfeng, a citizen of the United States, residing at Chicago, in the county of Cook, and State of Illinois, have invented a new, original, and ornamental Design for an Attachable Shelf, of which the following is a specification, reference being had to the accompanying drawing, forming part thereof.

I claim:

The ornamental design for an attachable shelf as shown.

In witness whereof, I hereunto subscribe my name, this 17th day of November, 1934.

JEAN SCHIMMELFENG.
